UNITED STATES PATENT OFFICE.

STANLEY R. HOWARD, OF MILTON, MASSACHUSETTS, ASSIGNOR TO PNEUMATIC SCALE CORPORATION, LTD., OF NORFOLK DOWNS, MASSACHUSETTS, A CORPORATION OF MASSACHUSETTS.

CARTON-FEEDING MACHINE.

Application filed March 5, 1926. Serial No. 92,384.

This invention relates to carton feeding machines, and involves certain improvements upon and refinements over the machine shown in my prior Patent No. 1,342,047, to 55
5 which reference is made as illustrating the general type of machine involved herein.

In my prior patent, the knock-down cartons were successively removed from the carton pack by a vertically reciprocating 10
10 opener blade which entered between the panels of the endmost carton in the pack and started to open the carton, whereupon an oscillating frame moved up against the front panel of the carton and swung the free panels 15
15 of the carton through an arc of approximately 180° against a revolving feed roll which passed the carton into a carton delivery way and thence out of the machine.

The machine of my prior patent was 20
20 wholly satisfactory, and my present invention simply aims to simplify the construction of such machine while retaining the features of advantage which characterized it over the prior art.

25
25 In my present invention, I omit the oscillating frame of my prior patent, together with its operating and adjusting mechanisms, and I cause the opener blade to perform the functions which said oscillating frame per- 30
30 formed in my prior patent. To accomplish this result, I use a carton opener of unique construction and operation.

According to my present invention, such 35
35 opener embodies two independently acting blades, one of which has reciprocating motion only and the other of which has both reciprocating and swinging movement. Both blades initially enter the endmost carton of the pack as a unit and partially open 40
40 the same, one of said blades acting to press the rear panel of the carton against the carton pack while the other blade swings the free panels of the carton laterally through an arc of approximately 180° about said 45
45 presser blade member as a fulcrum into a position of opposite collapse. During this action, a swinging transfer roll moves up against the carton and presses it against the revolving feed roll of my prior patent, which 50
50 feed roll in conjunction with the sweeper fingers of my prior patent acts to pass the carton through the carton delivery way and out of the machine, whereupon the swing-

ing transfer roll and the blades of the composite carton opener return to their original 55
55 positions in order to repeat the operation on the next exposed carton in the pack.

The construction and operation of my invention, together with a selected embodiment thereof which well illustrates the 60
60 principles involved, is described and shown in the accompanying specification and drawings, and the characteristic features of novelty are particularly pointed out in the ap- 65
65 pended claims. Throughout the specifica-
tion and drawings, like reference characters are correspondingly employed, and in the drawings:—

Fig. 1 is a fragmentary side view of a 70
70 carton feeding machine of standard type equipped in accordance with my invention.

Figs. 2 and 3 are front and plan views, respectively, thereof.

Fig. 4 is a fragmentary front view showing both members of the composite blade entered vertically from below as a unit into the endmost carton on the conveyor. 75
75

Fig. 5 illustrates in fragmentary plan a 80
80 position of rest of the composite blade relative to the endmost carton of the pack.

Fig. 6 is a section on the line 6—6 of 85
85 Fig. 4.

Fig. 7 is a fragmentary front view showing the composite blade in the position of Fig. 5. 85
85

Fig. 8 is a section on the line 8—8 of Fig. 7.

Fig. 9 is a fragmentary plan illustrating in full and dotted lines the transfer of the 90
90 carton from the carton pack to the carton delivery way.

Fig. 10 shows the composite blade ad- 95
95 vanced from the position of Fig. 8 to a position in which both blade members are about to enter the endmost carton, and

Fig. 11 is a fragmentary detail view illus- 100
100 trating the mechanism for imparting vertical reciprocating movement to the composite blade.

The cartons C upon which my machine 105
105 operates are of usual construction presenting each a front panel, a back panel and two connecting side panels, each of said panels having at its ends top and bottom closure flaps F adapted to be overfolded upon each 105
105 other to close the ends of the package. Pref-

erably, the bottom flap of one of the side panels is shortened, as indicated at F', Figs. 2, 4 and 7.

These cartons are supported in knock-down condition upon a pair of spaced horizontally disposed rails 1 constituting the carton feed conveyor of the machine, the cartons themselves being positioned vertically on end on said conveyor and constituting a pack which may be moved towards the delivery end of the conveyor, by any suitable feed mechanism, for successive individual removal therefrom by my novel carton opener and transfer mechanism.

At either side of the delivery end of the conveyor, I provide a series of spring clips 2 and 3 against which the opposite corners of the endmost carton of the pack are adapted to bear.

In the removal of the carton from the pack, these clips successively release their grip on the carton corners, the clips 2 at the left hand corner of the carton yielding first.

According to my present invention the cartons are successively removed from the carton pack by a composite blade embodying a presser blade A and a swinging blade B. The blade A has reciprocating motion in a vertical path only. The blade B follows the reciprocating motion of the blade A in its upward direction only so that both blades penetrate between the panels of the endmost carton as a unit. The blade A, however, pauses within the carton while the blade B swings laterally about a vertical axis to transfer the carton from the carton conveyor to the carton delivery way, then descends vertically, and swings laterally in the reverse direction to rejoin the blade A, which in the meantime has descended, to its original position, whereupon the cycle is repeated to withdraw the next succeeding carton from the pack.

The cycle is as follows:—

The blades A and B first move vertically upward together as a unit to enter between the shortened bottom side panel and the bottom back panel of the carton. The blade A presses the back panel of the carton rigidly against the pack and the penetration of both blades into the carton has the effect of partially opening the carton by bulging it to spring its left hand corner, Fig. 6, away from the pair of clips 2 which are holding it on the conveyor at this edge.

The blade B now starts to swing laterally to the right about a vertical axis as shown in dotted lines Fig. 9, carrying the free panels of the carton through an arc of approximately 180°, the blade A meanwhile holding the back panel of the carton flat against the carton pack so that the carton swings about said blade as a fulcrum. The carton is therefore first squared and after-

wards carried to the opposite extreme of collapse. This takes the spring out of the corners of the carton so that the carton will stay opened square naturally when released. During this action, the blade A remains up 70 inside the carton.

After the blade B has swung to the position shown in Fig. 9, both blades start to recede. The blade A only drops down to the level of the shortened panel F' of the 75 carton, that is to say, that it does not wholly clear the carton pack (see Fig. 2). As the carton is swung laterally by the blade B, the slot or slit which exists at the juncture of the bottom front and bottom side panels of 80 the carton permits the carton to be drawn free of the blade A, which is therefore left in position to clamp against the shortened panel of the next outermost carton in the pack.

The blade B continues to recede to the position of Fig. 4 and thereafter swings laterally to the left again until it rejoins the blade A which in the meantime has reached its lowermost position. At this time, both blades are ready to move vertically upward again together to enter the next carton of the pack. In fact, the cam which imparts vertical reciprocation to both blades is dwelled to cause the blade A to wait at the top of its stroke while the blade B makes its lateral swing and descends and to wait at the bottom of its stroke until the blade B makes its return lateral swing and rejoins it.

As the carton is swung through the dotted line position of Fig. 9, it is engaged by a swinging presser roll P, operating in timed relation to the blades A and B, and pressed lightly against a constantly revolving vertically disposed feed roll F^a by which the carton is moved in the carton delivery way W of the machine and from which way it is ejected by the swinging ejector fingers E, the feed roll F^a and ejector fingers E corresponding in function and result to those shown in my said prior patent.

The presser roll P is a free moving idler roll and has a limited swinging motion towards and from the stationary revolving knurled feed roll F^a. When the blades A and B are entered within the endmost carton of the pack, the presser roll P is in the position shown in full lines in Fig. 9. In this position, there is sufficient space between it and the stationary feed roll F^a to permit the adjacent corner of the carton to be swung in between said rolls by the blade B as shown in dotted lines, Fig. 9. After the blade B has commenced to descend from its dotted line position of Fig. 9, and in fact has approximately reached the limit of its downward motion, the presser roll P swings inwardly to clamp the carton against the revolving feed roll. In the 130

meantime, however, the ejector fingers E have moved in behind the feed roll F^a so as to engage the carton when it is delivered to the feed roll and push it along the carton delivery way. After the carton leaves the

roll P, this roll returns to its full line position shown in Fig. 9 in readiness to repeat its operation upon the next carton withdrawn from the pack.

10 The blades A and B are respectively formed on their opposing faces so that they may snugly fit one upon the other in their penetrating movement into the carton as a unit. For this purpose the blade A may 15 conveniently be grooved from end to end thereof to receive the blade B.

Sliding rectilinear motion in a vertical path to cause the blades A and B to simultaneously penetrate the endmost carton in 20 the pack from below is imparted to the blades from the cam shaft 4 of the machine by means of a cam 5 on said shaft. This cam is provided with a closed cam path within which tracks a cam roll 6 (Fig. 11) 25 carried by a cam lever 7. The cam lever 7 is forked at one end to straddle the drive shaft and is connected at its opposite end at 8 to the short arm of a bell crank lever 9. The bell crank lever 9 is fulcrumed on a 30 stub shaft 10 projecting from the frame of the machine.

Pivoted between its ends at 11 to the long arm of the bell crank lever is a thrust lever, one arm 13 of which is slidably connected 35 at 14 to the frame of the machine. The other arm 15 of said lever is forked, as shown in Fig. 4, and carries a cross rod 16 to which is clamped a strap 17 carrying the presser blade A. Depending from the 40 presser blade is an arm 18 to which one end of a coiled spring 19 is fastened, the other end of said spring being hooked about a stud 20 extending from the pivot 11. The purpose of the spring 19 is to urge the 45 the presser blade firmly against the rear panel of the endmost carton.

The swinging blade B is mounted to move with the presser blade A in its vertical penetrating movement into the carton and thereafter to swing laterally relative to said blade A. To this end, the blade B is mounted in a block 21 which is radially adjustable as at 22 (Fig. 4) on a horizontally disposed rocker arm 23 which is mounted to turn with 55 and to slide longitudinally along a vertical disposed squared rock shaft 24 journaled in suitable bearings 25 extending from the frame of the machine.

The shaft bearing for the arm 23 is 60 squared to fit said squared shaft 24 and turn therewith, and below said squared portion depends as a sleeve 26 loosely fitting said shaft and provided with an inwardly extending lug 27 adapted to overlie said cross rod 16 of the thrust lever 15 when the

parts are in the position of Figs. 2 and 4, so that the upward thrust of said lever will slide the arm 23 along the shaft 24, thereby raising the blade B simultaneously with the blade A.

The blade B is yieldingly pressed towards the blade A by a coiled spring 28 (Fig. 10), one end of which is anchored to an extension 29 of the rocker arm 23 and the other end of which is anchored to an 75 arm 30 depending from the blade B itself.

When both blades have reached the limit of their penetrating stroke into the carton, the blade A pauses while the blade B swings laterally to the right in Fig. 2. This is effected by rotating the shaft 24 through a partial revolution, and to effect this in properly timed relation to the operation of the other parts of the machine, I provide the cam shaft with an open cam 31 (Fig. 3), 80 which actuates the cam roll 32 of a cam lever 33 which is forked at one end to straddle the cam shaft and at its other end is linked at 34 to a rock shaft 35 journaled in a suitable bearing 36 at the base of the machine. The rock shaft 35 carries a gear segment 37 which meshes with a bevelled gear 38 on the lower end of the squared shaft 24, whereby to rock said shaft 24 to the right in Fig. 4, causing the blade B to 85 swing the carton clear of the pack, as shown in dotted lines Fig. 9, towards the vertically disposed revolving feed roll F^a. This roll is rotated from any driving shaft of the machine by means of the gear train indicated generally by the numeral 39 in Figs. 1 and 2, and the withdrawn carton is lightly 90 pressed thereagainst by the swinging presser roll P which has now swung inwardly against the carton, as shown in Fig. 9.

The presser roll is operated in properly timed relation by an open cam 40 on the cam shaft of the machine, through a cam roll 41 carried by a cam lever 42 which is fulcrumed on the stub shaft 10 and is linked at 43 (Fig. 3) to a bell crank lever 44, which is fulcrumed at 44' on the top of the machine frame. The bell crank lever 44 is 100 adjustably linked at 45 to a rocker arm 46 carried by a rock shaft 47 journaled vertically in suitable brackets 48, and provided with inwardly extending arms 49 within which the presser roll is vertically journaled, as appears in Fig. 1.

The carton is now lodged in the delivery way W and is ejected therefrom by the ejector fingers E which in the meantime have moved in behind the feed roll F^a in position to sweep the carton through said runway as it leaves said roll, whereupon the blades A and B and the swinging presser roll P return to their original positions to repeat the operation on the next carton in the pack.

Various modifications in the construction and operation of my machine may obviously be resorted to without departing from the spirit of my invention if within the limits of the appended claims.

What I therefore claim and desire to secure by Letters Patent is:

1. In combination, a support for a pack of collapsed cartons, and means constructed and arranged to enter the endmost carton of the pack and swing the front and side panels thereof into a position of opposite collapse, and a transfer member operating independently of said carton entering means and adapted to swing into engagement with said swinging carton to effect complete withdrawal thereof from the carton pack.
2. In combination, a support for a pack of collapsed cartons, a pair of blades, means for imparting simultaneous reciprocation to said blades to cause them to enter the endmost carton of the pack as a unit and partially open the same, and independently effective means for imparting independent swinging motion to one of said blades after the completion of said entering motion to cause it to swing the free panels of the carton about the other blade as a fulcrum and into a position of opposite collapse.
3. In combination, a support for a pack of collapsed cartons, a pair of blades, means for imparting simultaneous reciprocation to said blades to cause them to enter the endmost carton of the pack as a unit and partially open the same, and means for imparting independent swinging motion to one of said blades only to cause it to swing the free panels of the carton about the other blade as a fulcrum and into a position of opposite collapse, and a transfer member operating independently of said carton entering means and adapted to swing into engagement with said swinging carton to effect complete withdrawal thereof from the carton pack.
4. In a machine of the class described, a support for a pack of collapsed cartons, a pair of blades adapted to enter the endmost carton of the pack as a unit and partially open the same, one of said blades acting to press the rear panel of said carton against the carton pack while the other blade swings the free panels of said carton about said presser blade as a fulcrum into a position of opposite collapse, and a transfer member operating independently of said carton entering means and adapted to swing into engagement with said swinging carton to effect complete withdrawal thereof from the carton pack.

5. In a machine of the class described, a horizontal support for a pack of collapsed cartons, a pair of blades adapted to enter the endmost carton of the pack as a unit from below and partially open the same, one

of said blades acting to press the rear panel of said carton against the carton pack while the other blade swings the front and side panels of the penetrated carton laterally about said presser blade as a vertically disposed fulcrum into a position of opposite collapse, and a transfer member operating independently of said carton entering means and adapted to swing into engagement with said swinging carton to effect complete withdrawal thereof from the carton pack.

6. In a machine of the class described, a support for a pack of collapsed cartons, a pair of blades adapted to vertically enter the endmost carton of the pack as a unit and partially open the same, one of said blades acting to press the rear panel of said carton against the carton pack while the other blade swings the front and side panels of said carton laterally about said presser blade as a fulcrum into a position of opposite collapse, a revoluble feed member disposed adjacent the carton support, and a transfer member adapted to swing into engagement with said swinging carton and press it against said revoluble feed member.

7. In a machine of the class described, a support for a pack of collapsed cartons, a pair of blades mounted for both simultaneous and independent movement relative to each other and to the carton pack, means for imparting sliding rectilinear motion to said blades to cause them to enter the endmost carton in the pack as a unit and in such relation that one of said blades presses the rear panel of said carton against said pack, means for imparting swinging motion to the other blade to cause it to swing the panels of said carton about the presser blade as a fulcrum into a position of opposite collapse, both blades subsequently retreating in substantially parallel paths and said swinging blade finally rejoining said presser blade in position to repeat said cycle.

8. In a machine of the class described, a support for a pack of collapsed cartons, a pair of blades mounted for both simultaneous and independent movement relative to each other and to the carton pack, means for imparting sliding rectilinear motion in a vertical path to said blades to cause them to enter the endmost carton in the pack as a unit from below and in such relation that one of said blades presses the rear panel of said carton against said pack, means for imparting lateral swinging motion about a vertical axis to the other blade to cause it to swing the panels of said carton about the presser blade as a fulcrum into a position of opposite collapse, said blades subsequently retreating in substantially parallel paths and said swinging blade finally swinging laterally in the reverse direction and rejoining said presser blade beneath the carton pack.

9. In a machine of the class described, a

- support for a pack of collapsed cartons, a pair of blades mounted for both simultaneous and independent movement relative to each other and to the carton pack, means for imparting sliding rectilinear motion to said blades to cause them to enter the endmost carton in the pack as a unit and in such relation that one of the blades presses the rear panel of said carton against said pack, means for imparting swinging motion to the other blade to cause it to swing the panels of said carton about the presser blade as a fulcrum into a position of opposite collapse, said blades subsequently retreating in substantially parallel paths and said swinging blade finally swinging rejoining said presser blade in position to repeat said cycle, a revoluble carton feed member disposed adjacent the carton support, and a relatively movable member adapted to swing into engagement with said swinging carton and press it against said revoluble feed member.
10. In a machine of the class described, a support for a pack of collapsed cartons, a pair of blades, means including a thrust lever for imparting reciprocating motion to said blade, a rock shaft, a rocker arm mounted on said shaft to turn therewith and capable of sliding movement longitudinally of said shaft and carrying one of said blades, said arm disposed for actuation by said thrust lever when in one position whereby both blades are moved as a unit into the endmost carton of the pack to partially open the same, and means for rocking said rock shaft to cause the blade carried by it to swing the free panels of said carton into a position of opposite collapse.
11. In a machine of the class described, a support for a pack of collapsed cartons, a pair of blades, means including a thrust lever for imparting reciprocating motion to said blade, a rock shaft, a rocker arm mounted on said shaft to turn therewith and capable of sliding movement longitudinally of said shaft and carrying one of said blades, said arm disposed for actuation by said thrust lever when in one position whereby both blades are moved as a unit into the endmost carton of the pack to partially open the same, and means for rocking said rock shaft to cause the blade carried by it to swing the free panels of said carton laterally into a position of opposite collapse, said means including a gear on said rock shaft, a gear segment meshing therewith and a cam lever and operative connections from one of the cams on said cam shaft to said gear segment, a revoluble feed member disposed adjacent the carton support, a transfer roll adapted to swing about a vertical axis into engagement with the swinging carton and press it against said revoluble feed member and a vertically disposed rock shaft carrying said transfer roll and operatively connected with one of the cams on said cam shaft.
12. In a machine of the class described, a cam shaft having cams, a support for a pack of collapsed cartons, a pair of blades, a mount for one of said blades including a thrust lever, means for imparting vertical reciprocating motion to said mount includ-
- ing a bell crank lever operatively connected with said thrust lever and a cam lever operatively connected with said bell crank lever and actuated from one of the cams on said cam shaft, a vertically disposed rock shaft, a rocker arm mounted on said shaft to turn therewith and capable of sliding movement longitudinally of said shaft and carrying the other blade, said arm disposed for actuation by said thrust lever when in one position whereby both blades are moved vertically upward as a unit into the endmost carton of the pack to partially open the same, and means for rocking said rock shaft to cause the blade carried by it to swing the free panels of said carton laterally into a position of opposite collapse, said means including a gear on said rock shaft, a gear segment meshing therewith and a cam lever and operative connections from one of the cams on said cam shaft to said gear segment.
13. In a machine of the class described, a cam shaft having cams, a support for a pack of collapsed cartons, a pair of blades, a mount for one of said blades including a thrust lever, means for imparting vertical reciprocating motion to said mount including a bell crank lever operatively connected with said thrust lever and a cam lever operatively connected with said bell crank lever and actuated from one of the cams on said cam shaft, a vertically disposed rock shaft, a rocker arm mounted on said shaft to turn therewith and capable of sliding movement longitudinally of said shaft and carrying the other blade, said arm disposed for actuation by said thrust lever when in one position whereby both blades are moved vertically upward as a unit into the endmost carton of the pack to partially open the same, and means for rocking said rock shaft to cause the blade carried by it to swing the free panels of said carton laterally into a position of opposite collapse, said means including a gear on said rock shaft, a gear segment meshing therewith and a cam lever and operative connections from one of the cams on said cam shaft to said gear segment, 100
14. In combination, a support for a pack of collapsed cartons, and means constructed and arranged to enter the endmost carton of the pack and swing the front and side panels thereof, and a transfer member operating independently of said carton entering means and adapted to swing into engagement with said swinging carton to effect 105

complete withdrawal thereof from the carton pack.

15. In combination, a support for a pack of collapsed cartons, a pair of blades, means for imparting simultaneous reciprocation to said blades to cause them to enter the endmost carton of the pack as a unit and partially open the same, and means for imparting independently swinging motion to one of said blades only to cause it to swing the free panels of the carton about the other blade as a fulcrum.

16. In combination, a support for a pack of collapsed cartons, a pair of blades, means for imparting simultaneous reciprocation to said blades to cause them to enter the endmost carton of the pack as a unit and partially open the same, and means for imparting independent swinging motion to one of said blades only to cause it to swing the free panels of the carton about the other blade as a fulcrum, and a transfer member operating independently of said carton entering means and adapted to swing into engagement with said swinging carton to effect complete withdrawal thereof from the carton pack.

17. In a machine of the class described, a support for a pack of collapsed cartons, a pair of blades adapted to enter the endmost carton of the pack as a unit and partially open the same, one of said blades acting to press the rear panel of said carton against the carton pack while the other blade swings the free panels of said carton about said presser blade as a fulcrum, and

a transfer member operating independently of said carton entering means and adapted to swing into engagement with said swinging carton to effect complete withdrawal thereof from the carton pack. 40

18. In combination, a support for a pack of collapsed cartons, a pair of blades, means for imparting simultaneous reciprocation to said blades to cause them to enter the endmost carton of the pack as a unit and partially open the same, independently effective means for imparting independent swinging motion to one of said blades after the completion of said entering motion to cause said blade to swing the free panels of the carton about the other blade as a fulcrum, a revoluble feed member disposed adjacent the carton support, and a transfer member operating independently of said blades and effective to swing into engagement with said swinging carton and press it against said revoluble feed member. 45 50

19. In a machine of the class described, a support for a pack of collapsed cartons, a pair of blades, means for entering said blades as a unit into the endmost carton of the pack, independently effective means for swinging one blade relative to the other after the completion of said entering motion, both blades subsequently retreating in substantially parallel paths and said swinging blade finally rejoining the other blade in position to repeat said cycle. 55 60

In testimony whereof I affix my signature.

STANLEY R. HOWARD.
